UNITED STATES PATENT OFFICE.

GEORGE F. ANDERSON, OF WATERBURY, CONNECTICUT, ASSIGNOR TO SCOVILL MANUFACTURING COMPANY, OF WATERBURY, CONNECTICUT, A CORPORATION OF CONNECTICUT.

LIP STICK.

Application filed July 27, 1926. Serial No. 125,247.

This invention relates to certain improvements in holders for cosmetic preparations.

In dispensing certain cosmetics, such as lipsticks, facial creams and the like, it is desirable that the cosmetic be carried in its container so that by the manipulation of the container the cosmetic may be protruded beyond the end of the case for use and withdrawn within the container when not in use by a simple manipulation of the container. Cosmetics of the type referred to are generally applied to the person of the user by rubbing. Where the cosmetic is carried in a container from which it is protruded and withdrawn, it frequently happens that the pressure placed upon the cosmetic stick during use causes the stick to slide back into the container, thus causing a certain amount of annoyance to the user.

It is a special object of the present invention to provide a container for lipsticks and like cosmetics in which the cosmetic may be protruded and withdrawn, and in which the cosmetic is so supported in its container that it cannot be accidentally forced back into the container during use, so that after it has been once protruded it may be used as long as desired and then withdrawn or moved back into its container after its user is finished.

A further object of the invention is to provide an improved container for effecting this of simple form and of few parts in which the stick may be readily manipulated for use and non-use.

With these and other objects not specifically referred to, the invention consists in certain novel parts, arrangements and combinations which will be described in connection with the accompanying drawings and the novel features pointed out in the claims hereunto annexed.

Referring now to these drawings,—

Figure 1 is a side elevation of a container embodying the invention, the container being shown closed;

Figure 2 is a sectional view of the container shown in Fig. 1, the container being shown as open but the cosmetic withdrawn into the container;

Figure 3 is a view similar to Fig. 2 showing the cosmetic protruded for use;

Figure 4 is a sectional view of the container shown in the preceding figure, certain parts of the container being omitted to show the construction;

Figure 5 is a detail view showing one form of closure which may be used;

Figure 6 is a perspective view of one type of propeller which may be employed for protruding the cosmetic stick;

Figure 7 is a broken development view of the same, and

Figure 8 is a modified form of container which may be used within the invention.

Referring now to these drawings, the container is of a type in which the cosmetic is supported so that by rotating a part of the container a cosmetic may be protruded for use and withdrawn when the user has finished therewith. While various constructions may be employed for this purpose, in the particular construction illustrated the container comprises an outer casing 1 which is open at each end, this casing being stationary. Within this casing is rotatably supported a tube 2 of light metal or the like which is provided with a longitudinal slot 3. This tube 2 terminates in a head 4 which may conveniently form the bottom of the casing, this head being provided with a milled edge 5 to afford a convenient finger grip for rotating the tube, and being provided with a flange 6 which has a butt engagement with the end of the outer casing 1.

Within the tube 2 and having sliding engagement therewith, is a cosmetic holder in the form of a cup 7 in which is placed the cosmetic stick 8. This cup 7 is formed with a projection 9 which extends through and slides in the longitudinal slot 3, before referred to.

This cosmetic stick is projected beyond the casing 1 for use and withdrawn into the casing for non-use, an improved propelling means being provided for effecting this.

While the particular propelling device employed may vary in construction, it will be of such character, in accordance with the invention, that the cup is prevented from an accidental movement back into the casing due to a pressure on the end of the cosmetic stick. A convenient construction for effecting this is that shown, in which the tube 2 is surrounded by a helix, the propelling spiral of which is engaged by the projection 9 on the stick carrier 7. This helix being stationary, by rotating the tube 2, the projection 9 is given a rotary and a longitudinal movement so that it moves up and down in the slot 3, and this projects and retracts the cosmetic stick 8.

This helix may, of course, vary somewhat in construction, but as shown it is in the form of a sleeve 10 of light spring metal and is provided with an operating or propelling groove 5 11.

The means for preventing accidental movement of the cosmetic carrier into the casing may, of course, vary within considerable limits, but preferably these means will be in 10 the form of stops, a sufficient number of stops being provided to effect their function as the cosmetic wears down and the cosmetic carrier is projected further and further toward the dispensing end of the casing. In 15 the best constructions, however, for convenience in manufacturing and assembling, these stops are formed on the helix and, as shown, the helix is cut away to form shoulders 12, three such shoulders being in stepped relation, and as shown in Fig. 7. It is, of course, understood that any number of such shoulders desired may be employed. With this construction, as the tube is rotated, the projection follows the propelling groove 11 and 20 rises above one of these stops. If now a direct pressure be exerted on the end of the lipstick, such as that occasioned by its use, the projection will be forced against one of these stops and a further rear movement of 25 30 the projection cannot take place until the tube has been rotated in a reverse direction to clear the projection from the shoulder. With this construction, therefore, the lipstick cannot be accidentally forced back into the 35 container.

The sleeve may be positioned in the casing in any suitable manner. In the particular construction shown, the tube 2 is provided near its outer end with a bead 13 and the 40 sleeve 10 being resilient may be forced past this bead and against the flange 6 of the head 4 of the tube before referred to, the sleeve being thus securely held in position.

The container may be closed in any suitable 45 manner. As shown in Fig. 2, there is provided a cap 14 hinged to the container by means of a wire pintle 15 held in a bead 16 formed in the outer end of the casing 1. If desired, however, it may be closed by an ordinary slip cap 17, such as shown in Fig. 8.

With the construction shown and described, it will be seen that a very compact and simple container has been provided, and one in which accidental displacement during 55 use is effectually prevented.

While the invention has been shown and described in its preferred form, it will be understood that various changes may be made in the propelling means and in the form

of the stops without departing from the invention as defined in the appended claims. 60

What I claim is:

1. In a holder for cosmetics and the like, the combination of an outer casing, a cosmetic holder mounted in the casing so as to 65 have a longitudinal movement therein, a propelling device for moving the holder in either direction, and stops concealed within the casing and with which the cosmetic holder is brought into engagement by pressure applied to a cosmetic carried in the holder for preventing inward longitudinal movement of the holder during the use of the cosmetic, said stops being released by a reverse movement of the propelling device. 70

2. In a holder for cosmetics and the like, the combination of an outer casing, a cosmetic holder mounted in the casing so as to have a longitudinal movement therein, a propelling device for moving the holder in 80 either direction, and stops concealed within the casing and with which the cosmetic holder is brought into engagement with pressure applied to a cosmetic carried in the holder, said stops cooperating with the propelling devices for preventing inward longitudinal movement of the holder during the use of the cosmetic, said stops being released by a reverse movement of the propelling device. 85

3. In a holder for cosmetics and the like, the combination of an outer casing, a rotatable tube in the casing having a longitudinal slot, a cosmetic holder in the tube and provided with a projection extending 90 through the slot, a helix engaged by the projection for effecting a longitudinal movement of the holder in the casing and shoulders on the helix arranged for engagement by the projection on application of pressure applied to a cosmetic carried in the holder to prevent the carrier from inward longitudinal movement during the use of the cosmetic. 100

4. In a holder for cosmetics and the like, the combination of an outer casing, a rotatable tube in the casing having a longitudinal slot, a cosmetic holder in the tube and provided with a projection extending through the slot, a spring sleeve having a propelling groove engaged by the projection, and shoulders formed in the wall of the groove with which the projection engages on application of pressure to a cosmetic carried in the holder for preventing rearward movement of the holder during use of the cosmetic. 110

In testimony whereof, I have hereunto set my hand.

GEORGE F. ANDERSON.
